UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

SEPARABLE CONNECTOR FOR ELECTRICAL CONDUCTORS.

1,145,424.

Specification of Letters Patent.

Patented July 6, 1915.

Application filed January 13, 1913. Serial No. 741,775.

To all whom it may concern:
Be it known that I, CHARLES J. KLEIN, a citizen of the United States, residing at Milwaukee, in the county of Milwaukee and State of Wisconsin, have invented new and useful Improvements in Separable Connectors for Electrical Conductors, of which the following is a full, clear, concise and exact description, reference being had to the accompanying drawing, forming a part of this specification.

My invention relates to separable connectors for electrical conductors. It has among its objects to provide an improved longitudinally separable connector wherein the contact members engage each other snugly in such a manner as to prevent accidental longitudinal separation thereof and the bases carrying the same are locked against relative rotation by means independent of the contacts.

Other objects and advantages of my improved construction will hereinafter appear.

In order that my invention may be fully and clearly disclosed, I have illustrated one embodiment of the same in the accompanying drawings.

Figure 1 is a central longitudinal view of the two parts of the connector positioned one above the other. Fig. 2 is a transverse sectional view of the connector in circuit closing position. Fig. 3 is a perspective view of the contact members.

The device illustrated herein is of the single pole type. It comprises an insulating base 1 carrying contacts 3 and 4 therein and adapted to receive a second insulating base 2 carrying a single contact member 5, the said bases being longitudinally separable but locked against relative rotation and accidental longitudinal separation.

The base 1 is substantially cylindrical in shape and is provided in its lower end with a chamber 6 of substantially cylindrical shape, which communicates with a smaller chamber 7 above the same. A conductor groove 8 is provided in the upper end of the base 1 leading to the recess 7, to permit the conductor to be brought in to the same. The contact members 3 and 4 are embedded in the top of the base and extend vertically downward parallel to each other through the center of the chamber 6 into the chamber 7. The contact member 3 is rigid. The

contact member 4 is lighter and resilient. 55 Near its lower end the resilient member 4 is provided with an inwardly extending projection or knob 9 having a function hereinafter described. In a preferred form a terminal member 10 is formed integral 60 with the rigid contact 3 and is bent back therefrom substantially at right angles, so that it protrudes opposite the conductor opening 8. In order to attach the conductor to this terminal member, a binding screw 65 11 is provided.

The base 2 is provided with a single contact 5 which extends vertically upward in a chamber 12 formed therein and has its lower end embedded in the material of the 70 base in substantially the same manner as the contacts 3 and 4 already described. This contact is likewise rigid and near its upper end is provided with a slightly elongated rounded opening 13 adapted to receive the projection 9 on the resilient contact 4 when the contact 5 is forced in between the contacts 3 and 4. As in the case of the contact 3 on the base 1, this contact 5 on the base 2, is likewise provided with an integral terminal lug 14 extending substantially at right angles thereto and carrying a binding screw 75 15. In a preferred form this lug likewise extends over a vertically extending conductor opening 16 which communicates with 80 the chamber in which the contact 5 is carried.

In order to prevent the angular rotation of the two parts of the device and the consequent strain on the contact members, I 90 preferably provide the base 2 with a flattened surface 17 on one side of the same, preferably the side opposite the conductor opening 8 and provide a correspondingly shaped wall for the chamber 6 in the base 95 1. As shown in Fig. 1, I also preferably provide a horizontally disposed edge or shoulder 18 adjacent this flattened surface, which is adapted to engage with the lower edge of the base 1 when the two bases are 100 brought together, and serve as a stop to prevent the two parts from being forced too far into each other. In a preferred form I also provide a shoulder 19 at the top of the chamber 6, which is adapted to engage the 105 top of the base 2 at the same time that the shoulder 18 engages the bottom of the base 1. In this way I am able to limit the move-

ment of the members 1 and 2 without imposing any undue strain on any of the contacts.

When it is desired to connect the device in circuit, the ends of the conductor are attached to the binding screws on the terminal plates. By reason of the fact that the contact screws are accessible through the open ends of the members 1 and 2, this process 10 of attaching the conductors is rendered very simple. In order to close the circuit, the member 2 is inserted in the base 1, whereupon the contact member 5 passes between the contacts 3 and 4 and is locked in position by the snapping of the projection 9 on the resilient contact 4, into the opening 13 in the contact 5. At the same time the flattened side 17 on the base 2 engages the corresponding flattened side on the base 1 and 20 the parts are locked against rotation.

Obviously, my improvement is not limited in its application to single pole connectors, but may be adapted to use in connection with double pole devices, if desired. 25 This, and various other modifications which will be evident to one skilled in the art all fall within the purview of my invention.

What I claim as new and desire to secure by Letters Patent is:—

20 1. A separable connector comprising a

pair of bases, one receivable in the other and each having conductor openings in its ends, contact members engaging each other when the bases are brought together and having laterally extending integral terminal members protruding substantially at right angles thereto adjacent said conductor openings, and means independent of said contact members for preventing relative rotation of said bases. 35

2. A separable connector comprising telescoping molded bases having recesses on their adjacent faces, the interfitting portions of said bases being of non-circular cross-section to permit their telescoping only in 40 a single rotary relation and to thereafter hold the same against relative rotation, a pair of contact fingers molded in one of said bases and disposed in the recess thereof, and a contact finger molded in the other of said 45 bases and disposed in the recess thereof, said contacts interlocking to hold said bases against separation.

In witness whereof, I have hereunto subscribed my name in the presence of two 50 witnesses.

CHARLES J. KLEIN.
